UNITED STATES PATENT OFFICE.

WILLIAM B. POTTER, OF SCHENECTADY, NEW YORK, ASSIGNOR TO GENERAL ELECTRIC COMPANY, A CORPORATION OF NEW YORK.

ELECTRIC-RAILWAY SYSTEM.

SPECIFICATION forming part of Letters Patent No. 712,961, dated November 4, 1902.

Application filed March 5, 1900. Serial No. 7,260. (No model.)

To all whom it may concern:

Be it known that I, WILLIAM B. POTTER, a citizen of the United States, residing at Schenectady, county of Schenectady, State of New York, have invented certain new and useful Improvements in Electric-Railway Systems, (Case No. 1,067,) of which the following is a specification.

This invention relates to methods of current-supply for electric railways in general, and with especial reference to surface-contact systems, in which it is not desirable to maintain current of high potential permanently upon the working conductors, which are engaged by the collectors carried by the car.

The object of the invention is to provide a sectional-conductor alternating-current railway system in which the surface-conductor sections are normally maintained at a potential not inimical to animal life and in which the potential of these sections can be automatically increased to the desired degree for operating the car-motors by the passage of the car which carries the motors. This object is obtained, in conjunction with the advantageous feature of reducing the fixed losses of transformer-cores, in the manner described in the patent to Ferranti, No. 409,775, 30 August 27, 1889.

The invention herein may also be applied to systems other than railway systems.

Figures 1 and 2 are diagrammatic illustrations of certain features of my invention, and 35 Figs. 3 and 4 are diagrams illustrating the application of these features with others.

In the particular system illustrated three mains L, M, and N are shown, which are supplied with current from any suitable source 40 of three-phase alternating current; but the invention is not limited in its application to a current of any specific number of phases.

In Fig. 1, P represents the primary of a three-phase transformer permanently connected to the mains L, M, and N. A secondary s cooperates with the primary P to normally supply three-phase current of low potential to the conductor-sections T T' and to one or both of the track-rails R, which rails 50 serve as the third conductor. These transformers may be single multiphase trans-

formers or may consist of groups of single-phase transformers. In either case they are provided with two sets of secondary coils S and s. Assuming that a current having a potential of ten thousand volts is maintained in the mains, the secondary s is constructed to supply current to the working conductors T, T', and R at a lower potential—for example, one hundred volts—and when the collectors 60 of the car engage with these working conductors the electromagnetic switch W is actuated by the low-potential current to disconnect the secondary s from the working conductors T T' and to connect the latter with 65 the secondary S, which is constructed to supply a working current of one or two thousand volts, as required, to operate the car-motors.

In order to avoid the fixed losses in the iron cores of the primary P in the arrangement 70 shown in Fig. 1, the method illustrated in Fig. 2 has been devised. In this case a small transformer has its primary p permanently connected to the mains and its secondary s permanently connected to the working conductors. A large transformer has its primary P normally disconnected from the mains and its secondary S normally electrically independent of the working conductors. Each transformer supplies current to the working 75 conductors at the same high potential, and when the working conductors are engaged by the collectors on the car the electromagnetic switch W connects the transformer P S with the mains and working conductors, so that 80 the two transformers supply current to the working conductors in parallel. This arrangement has, however, the objection that current of high potential is always supplied to the working conductors, and to obtain 85 the advantages of both the arrangements shown in Fig. 1 and Fig. 2 that shown in Fig. 3 has been devised. In this case the small-transformer normally supplies current at lower potential to the working conductors than does 90 the large transformer, and when the working conductors are engaged by the collectors carried by a car the high-potential transformer, which is normally disconnected from the mains and working conductors, is 95 operationally connected therewith and the secondary s of the low-potential transformer is cut out.

The core losses of the primary p of the low-potential transformer are not regarded as serious; but, if necessary, the electromagnetic switch W could be adapted to cut out this primary p when the high-potential transformer is connected to the mains and working conductors. It is necessary to cut out the low-potential transformer when the high-potential one is cut in, because otherwise there would be a short circuit around both transformers. It is not essential that both the primary P and secondary S be normally cut out, as the arrangement would be operative and economical if only the primary P be normally cut out.

In the arrangement shown in Fig. 4 the necessity of cutting out the small or low-potential transformer is obviated by compounding it in such manner that when the large or high-potential transformer is cut in the low-potential transformer will supply current to the working conductors at a higher potential than it normally does and at the same potential as the current supplied by the high-potential transformer. This is accomplished in the following manner: The primary p of the low-potential transformer is permanently connected with the mains. The secondary s of the low-potential transformer and the secondary S of the high-potential transformer are permanently connected in parallel with the working conductors T , T' , and R . The core losses in the secondary S when thus connected in parallel with the low-potential secondary s will not ordinarily be serious; but if they should prove to be so under peculiar conditions I wish it to be understood that the secondary S may be connected as shown in Fig. 3. Independent secondary coils s' are connected in series with the secondary s of the low-potential transformer, and primaries p' , normally disconnected from the mains, are adapted to coöperate with said independent or auxiliary coils. The primary P of the high-potential transformer is also normally disconnected from the mains.

Let us assume, for example, that a current of one hundred volts is normally supplied from the secondary s to the working conductors, and, as before, that the current of ten thousand volts is maintained on the mains, and that, furthermore, the transformers p', s' , the primaries p' of which are normally disconnected from the mains, are adapted to supply a current of nine hundred volts to the working conductors, while the transformer P, S supplies one thousand volts to the working conductors. Then when the working conductors are engaged by the collectors of a car the electromagnetic switch W will be actuated by the low-potential current to connect the primaries p' and the primary P with the mains, whereupon the compound transformer built up around the primary p will supply current at one thousand volts to the working conductors in parallel with the large transformer P, S ,

which is also supplying current at one thousand volts.

The small transformer will operate in the manner described if the legs of the primary P are disconnected from the lines leading from the electromagnetic switch W to the primaries p' , and hence the high-potential transformer P, S may be dispensed with, if desired, since the small transformer completely fulfils the requirements of maintaining normally a low potential on the working conductors and supplying a working current of higher potential when a car traverses that portion of the road which is controlled by that transformer. In this case the construction of the compound transformer should be suitably modified for the purpose by the use of larger cores and windings of larger cross-section than those used when the high-potential transformer is a part of the system. The auxiliary coils s' will normally operate as reactances in the transformer, but only during the time of flow of the low-potential current, and will not seriously affect the desired results.

In practice it is preferred that at least two of the working conductors T and T' be divided into sections A B B' , the current supplied to each section being controlled by the methods described. The track-rails R may be permanently connected to one side of the secondary three-phase system, as shown and described above.

The combination is claimed, broadly, herein of a transformer secondary which supplies current at low potential to the working conductors, a high-potential transformer-secondary which is cut into circuit automatically, and means for preventing a short circuit. The specific means for preventing short-circuiting illustrated in Fig. 4 is also claimed herein; but the means shown in Figs. 1 and 3 is not claimed, as it forms the subject-matter of a divisional case.

What I claim as new, and desire to secure by Letters Patent of the United States, is—

1. In an electric-railway system, the combination with the feeders and working conductors, of a transformer adapted to normally supply current of low potential to said conductors, a second transformer, and an electromagnetic switch actuated by the low-potential transformer, upon the passage of a car, to connect the second transformer so that a current of higher potential will be supplied to said conductors.

2. In an electric-railway system, the combination with the feeders and working conductors, of a transformer normally supplying current of low potential to said conductors, a second transformer, and an electromagnetic switch actuated by the low-potential transformer, upon the passage of a car, to coöperate with the first transformer to supply a working current of higher potential to said conductors.

3. In an electric-railway system, the combination with the feeders and working conductors, of a compound transformer adapted to normally supply current of low potential to said conductors, a second transformer normally operatively disconnected from the feeders, and an electromagnetic switch operated by the low-potential transformer, upon the passage of a car, for causing both transformers to supply a working current of higher potential in parallel to said conductors. 5
4. In an electric-railway system, the combination with the feeders and working conductors, of a compound transformer having some coils adapted to normally supply current of low potential to said conductors, and having normally inoperative coils adapted to co-operate with said coils to supply working current of higher potential to said conductors, 15 and an electromagnetic switch operated by said low-potential current, upon the passage of a car, to cause said co-operating coils to become operative. 20
5. In a system of distribution, the combination with the mains, of a transformer having its primary connected therewith, independent primary coils normally operatively disconnected from the mains, independent secondary coils in series with the secondary coils of said transformer and co-operating with said independent primary coils, and means for causing the independent primary coils to be operatively connected with the mains. 25
6. In an electric-railway system, the combination with the feeders, of working conductors, a transformer having its primary connected with the feeders and its secondary with the working conductors, independent primary coils normally operatively disconnected from the feeders, independent secondary coils in series with the secondary coils of said transformer and co-operating with said independent primary coils, an electromagnetic switch operated by the current in the secondary of 35 said transformer, for connecting said independent primary coils to be operated by the feeders. 40
7. In an electric-railway system, the combination with the feeders, of working conductors, a low-potential transformer connected with the feeders and working conductors, a transformer of relatively higher potential and normally inoperative by the feeders, independent primary coils normally operatively disconnected from the feeders, independent secondary coils in series with the secondary of said low-potential transformer and co-operating with said independent primary coils, and an electromagnetic switch 45 operated by the low-potential current, for connecting said independent coils and the high-potential transformer so as to be operated by the feeders. 50
8. In an electric-railway system, the combination with the feeders, of working conductors, a low-potential transformer connected with the feeders and working conductors, a transformer of relatively high potential normally operatively disconnected from the feeders, and having its secondary connected in parallel with the secondary of the low-potential transformer, independent primary coils normally operatively disconnected from the feeders, independent secondary coils in series with the secondary coils of the low-potential transformer and co-operating with said independent primary coils, and an electromagnetic switch operated by the low-potential current to connect the primary of the high-potential transformer and the independent primary coils so as to be operated by the feeders. 55
9. In an electric-railway system, the combination with the feeders and working conductors, of a transformer connected with the feeders and said conductors, and adapted to normally supply current of low potential to said conductors, and adapted to be compounded to supply higher potential, a second transformer adapted to supply current of higher potential to said conductors and normally inoperative by the feeders, and an electromagnetic switch operated by the low-potential current, on the passage of a car, to connect the high-potential transformer to be 60 operated by the feeders and to cause the first transformer to supply current of the same potential as the high-potential transformer to the working conductors, in parallel with the high-potential transformer. 65
10. An alternating-current electric-railway system, which comprises high-potential feeders, working conductors, a transformer secondary co-operating with the feeders to normally supply a current of low potential to the working conductors, and another transformer secondary co-operating with the feeders to supply current at a higher potential than the first secondary, to the working conductors, during the passage of a car there-over. 70
11. In an alternating-current system, the combination with the mains, of a transformer secondary adapted to co-operate with the mains to supply current of lower potential than that flowing in the mains, a second transformer secondary adapted to supply current of higher potential than that supplied by the first secondary, and means controlled by the first secondary for connecting the second secondary in circuit and preventing a short circuit through the first transformer. 75
12. In an electric-railway system, the combination with the feeder and sectional working conductors, of a transformer adapted to normally supply current of low potential to said conductors, a second transformer adapted to supply current of higher potential to said conductors, and an electromagnetic switch actuated when a car closes the circuit of the first secondary, to cut the second secondary into circuit and prevent a short circuit of the first secondary. 80
13. In a system of distribution for alternat-

- ing currents, the combination with the mains of a transformer secondary coöperating therewith to normally supply current of lower potential than that of the feeders, and another 5 transformer secondary coöperating with the feeders and with the first secondary, to automatically supply current of higher potential than that supplied by the first secondary, when required.
- 10 14. In a system of distribution for alternating currents, the combination with the mains or feeders, of a transformer secondary coöperating therewith to normally supply current of lower potential than that of the feeders, 15 another secondary coöperating with the feeders to supply current of higher potential than that supplied by the first secondary, and an electromagnetic switch operated by the low-potential current to cause the other secondary 20 to become operative.
- 15 15. In a system of distribution, the combination with the mains, of a transformer coöperating therewith to supply current of lower potential than that flowing through the mains, 25 a second transformer of higher potential than that supplied by the first, and normally disconnected from the mains, and an electromagnetic switch operated by the low-potential current, for connecting the second transformer 30 with the mains.
16. A transformer having auxiliary coils in series with its secondary, and independent primary coils adapted to coöperate with said auxiliary coils.
- 35 17. A transformer having its primary and secondary windings adapted to be normally connected to the mains and load, auxiliary coils in series with its secondary, independent primary coils, normally disconnected 40 from the mains and adapted to coöperate with the auxiliary coils, and a switch for connecting the independent primary coils with the mains.
18. In an electric-railway system, the combination with the feeders and working conductors, of a compound transformer comprising coils adapted to normally supply low-potential current to said working conductors, and auxiliary coils adapted to coöperate with 45 said coils to supply current to said working conductors at a higher working potential when a car is on said conductors.
19. In an electric-railway system, the combination with the feeders and working conductors, of a transformer adapted to supply current at low potential to said conductors normally, a transformer adapted to supply current at high working potential to said conductors during the passage of a car, and 55 60 means for preventing a short circuit through said transformers.
20. In an electric-railway system, the combination with feeders and working conductors, of a transformer having part of its pri-
- mary directly connected with said feeders and 65 its secondary connected with said working conductors, whereby it may normally transmit current of low potential to the latter, and means actuated by said low-potential current for connecting the whole of said primary to 70 said feeders, whereby current of higher potential is supplied to the working conductors during the passage of a car.
21. In an electric-railway system, the combination with the feeders and working conductors, of a transformer adapted to normally supply current of low potential to said conductors, a second transformer, and an electromagnetic switch actuated by the low-potential current, upon the passage of a car, 75 80 to connect the second transformer so that a current of higher potential will be supplied to said conductors, said switch being maintained in the position to which it has been moved by the current flowing from the secondary of the second transformer.
22. In an electric-railway system, a source of high-potential current, a source of low-potential current independent of the car, working conductors from which the current 90 for operating the car-motors is collected, said low-potential source being normally connected to, and said high-potential source being normally disconnected from said working conductors, and means operated by the low-potential current for connecting said high-potential source with said working conductors upon the passage of a car. 95
23. In an electric-railway system, a source of high-potential current, a source of low-potential current independent of the car, working conductors from which the current 100 for operating the car-motors is collected, said low-potential source being normally connected to, and said high-potential source being normally disconnected from said working conductors, and electromagnetic switches operated by current from said low-potential source to connect said high-potential source to the working conductors upon the passage 105 of a car. 110
24. In an alternating-current system, the combination with high-potential feeders and working conductors, the track rail or rails forming one of said conductors, of a low-potential transformer normally operatively connected with said feeder and working conductors, a high-potential transformer normally operatively disconnected from said conductors, and means for connecting said high-potential transformer to said working conductors. 115 120

In witness whereof I have hereunto set my hand this 2d day of March, 1900.

WILLIAM B. POTTER.
